DESIGN FOR A COMBINED GAS STORAGE TANK AND INSTRUMENT HOUSING

Edward H. Gill, Memphis, Tenn., assignor to J. T.
Gregory, Little Rock, Ark.

Application January 20, 1940, Serial No. 89,609

Term of patent 3½ years

To all whom it may concern:

Be it known that I, Edward H. Gill, a citizen of the United States residing at Memphis, in the county of Shelby and State of Tennessee, have invented a new, original, and ornamental Design for a Combined Gas Storage Tank and Instrument Housing, of which the following is a specification, reference being had to the accompanying drawing, forming a part thereof.

Fig. 1 is a side elevational view of the combined gas storage tank and instrument housing, showing my design; and

Fig. 2 is a top plan view thereof.

I claim:

The ornamental design for a combined gas storage tank and instrument housing, as shown.

EDWARD H. GILL.
